Primary Examiner — Catherine S Posthauer

(57) **CLAIM**

The ornamental design for a potion bottle stopper, substantially as shown and described.

DESCRIPTION

FIG. 1 is a front view of a first embodiment of a potion bottle stopper in accordance with the present invention, the rear view being a mirror image thereof;

FIG. 2 is a perspective view thereof;

FIG. 3 is a left view thereof, the right view being a mirror image thereof;

FIG. 4 is a top view thereof;

FIG. 5 is a bottom view thereof, with the environment removed.

FIG. 6 is a front view of a second embodiment of a potion bottle stopper in accordance with the present invention;

FIG. 7 is a perspective view thereof;

FIG. 8 is a top view thereof;

FIG. 9 is a bottom view thereof, with the environment removed.

FIG. 10 is a front view of a third embodiment of a potion bottle stopper in accordance with the present invention;

FIG. 11 is a perspective view thereof;

FIG. 12 is a top view thereof; and,

FIG. 13 is a bottom view thereof, with the environment removed.

The broken lines are shown for the purpose of illustrating environmental subject matter of an exemplary bottle and form no part of the claimed design.

1 Claim, 13 Drawing Sheets
